A. BEAM.

CLAMP DERAIL.

APPLICATION FILED MAR. 20, 1918.

Patented Feb. 18, 1919.

UNITED STATES PATENT OFFICE.

ALBERT BEAM, OF ROSE HILL, ILLINOIS.

CLAMP-DERAIL.

1,294,602.

Specification of Letters Patent. Patented Feb. 18, 1919.

Application filed March 20, 1918. Serial No. 223,527.

To all whom it may concern:

Be it known that I, ALBERT BEAM, a citizen of the United States, a resident of Rose Hill, in the county of Jasper and State of Illinois, have invented new and useful Improvements in Clamp-Derails, of which the following is a specification.

This invention relates to improvements in what I call a clamp derail; that is, a derailment device which may be secured in position without the necessity of utilizing bolts, spikes and the like, and this is one of the principal objects of this invention.

Another object of this invention, is the provision of a device of this kind in which the derailment device proper throws the car outwardly of the rail, rendering the device less likely to breakage and injury to accidental causes, such as a fallen brake-beam, and the like.

To the accomplishment of the foregoing and such other objects as may hereinafter appear, my invention consists in the combination, construction and arrangement of parts hereinafter described and then sought to be defined in the appended claims, reference being had to the accompanying drawings forming a part hereof, and which shows merely for the purpose of illustrative disclosure, a preferred embodiment of my invention, it being understood that various changes may be made in practice within the scope of the claims, without digressing from my inventive idea.

In the drawings,

Figure 1 represents an outside elevation of a railroad rail, with a device embodying my invention applied thereto;

Fig. 2 is a top plan view of the same;

Fig. 3 is a section through the railroad rail, showing my device in end elevation, the open position being shown in dotted lines;

Fig. 4 is a horizontal section taken through the device, substantially on line 4-4 of Fig. 3.

Referring now to the drawings, the numeral 1 designates the ties on which are mounted or secured the rails 2. The "clamp derail" includes the base or support 3 which is adapted to fit under the rail as shown clearly in Fig. 3, and is provided with the cut-out portion having the throat 4, leading to the wider cut-out portion 5, which

is shaped to fit and support the base of the rail as shown, particularly in Fig. 3. This portion is also additionally cut out as at 6, to receive the securing wedge member 7, this cut out portion 6 having a slightly tapered side and the wedge member 7 being slightly tapered and also having the groove or recess 8 cut out to fit and receive the edge of the base of the rail as shown clearly in Figs. 3 and 4. It is therefore obvious that when the device is positioned in proper relation to the rail and the key or wedge 7 driven home, it will be securely held against displacement.

The derailment device itself comprises the member 9 having the dependent arms 10 which are spaced apart and pivoted to the base by means of the pin 11, as shown. This derailment member has the comparatively elongated extension 12, which slopes up gradually from its outer edge as indicated at 13 to the enlarged abutment or stop member 14, so that as the wheels of the car engage the sloping surface, they will gradually be lifted until they reach the stop or abutment 14 and will then be thrown off the rail, thus accomplishing the function and purpose of the device.

The web 15 is provided on the base and extends between the spaced legs or arms 10 on the derailment device, being provided with the aperture 16 to receive the padlock or other suitable locking means 17, whereby the derailment device may be held in derailing or open position, as is well understood.

It is to be noted that the under side of the derailment member is cut away as at 18 to receive the tread of the railroad rail, and also that the derailment member proper has an extension 19 which practically covers the web 15 and locking means 17 to guard the same against accident.

It is also to be noted that the derailment device is mounted so that it swings outward relative to the rail and therefore is not liable to breakage or other injury when in open position, due to a fallen brake-beam or other causes.

It is therefore obvious that I have provided a device which is exceedingly simple and strong in construction, which may be readily applied in position without the necessity of the use of bolts, spikes or the like,

with a minimum amount of time and trouble, and which will operate efficiently to accomplish the desired purpose.

What I claim is:—

- 5 1. In a derailing device, in combination, a base member to lie below and project on opposite sides of the rail, a wedge to bear against the inside of the rail and said base to removably secure the latter on said rail,
- 10 10. a derainment device having a part to overlie the rail and a depending body having a pivotal connection with the base next the outside of the rail, whereby the device may be swung outwardly with reference to the rail.
- 15 2. In a derailing device, in combination, a base to be attached to a rail and having a wedge seat next the inside of the rail, a wedge to fit the wedge seat and clamp the base to the rail, said wedge having a groove to receive a rail flange, a derainment device having spaced legs to straddle a part of said base, and means to pivotally connect the lower ends of said legs to said base next the outside of said rail, whereby the derainment device may be swung outward with reference to the rail.
- 20 3. In a derailing device, in combination, a base having a rail seat and also formed with a wedge seat next the inside of the rail, a wedge to fit the wedge seat and arranged to have a bearing against a flange of the rail, a derainment device having a seat to receive the "ball" of the rail, means for pivotally attaching said device to the base next the outside of the rail to permit said device to be swung outward with reference to the

rail, and means on said base to which may be attached a lock for locking the said device in derailing position.

4. In a derailing device, in combination, a base adapted to fit under a rail between the ties and having portions lying inside and outside of the rail, the inside portion of said base having a wedge seat next the rail, and said outside portion of said base having a central extension, a wedge to fit said wedge seat and also bear against a flange of the rail to lock the base to the rail, a derainment device having spaced legs adapted to straddle said central extension of the base, means for pivotally connecting the lower ends of said legs to said base in a manner to permit said device to swing outwardly with reference to said rail, and means to engage said central extension of the base to lock said device in derailing position.

5. A derailing device, including in combination, a base having a rail seat and a wedge seat adjacent said rail seat, a wedge to fit said wedge seat and adapted to have a bearing against and longitudinally of the rail, a central extension from the outside of said base, a derainment device, legs on said device straddling said central extension, and means for pivotally connecting said legs to said base, so as to permit said device to be swung over and above said base and also away therefrom.

In witness whereof, I have hereunto affixed my hand this 14th day of March, 1918.

ALBERT BEAM.
